F. W. WIESEBROCK.
Pressure Regulator and Indicator.

No. 221,885.

Patented Nov. 18, 1879.

FIG. I.

FIG. II.

UNITED STATES PATENT OFFICE.

FREDERICK W. WIESEBROCK, OF NEW YORK, N. Y.

IMPROVEMENT IN PRESSURE REGULATORS AND INDICATORS.

Specification forming part of Letters Patent No. **221,885**, dated November 18, 1879; application filed October 29, 1879.

To all whom it may concern:

Be it known that I, FREDERICK W. WIESEBROCK, of the city, county, and State of New York, have invented certain new and useful Improvements in Pressure Regulators and Indicators, of which the following is a specification.

The object of my invention is to construct an improved pressure regulator and indicator; and it consists in the construction and arrangement of the parts, as will be more definitely described hereinafter, reference being had to the accompanying drawings and the letters of reference marked thereon.

In the accompanying drawings, Figure I is a vertical longitudinal section of my pressure-regulator. Fig. II is an end view of the same, showing the indicator-gage.

In the drawings, A represents the body of my device, having four branches, the lower one, *a*, being screwed or tapped into a vessel containing the fluid under pressure, while the branch *b* is connected with a pipe.

In the branch *c* is arranged a diaphragm and valve connected to a weighted lever, spring, or equivalent. At the outer end of this branch is a suitable cock, *C*, to allow the air or gas to escape when desired.

In the branch *c* are arranged two curved channels, *D* and *E*, the latter forming at its upper end a seat for the valve *e*, which is provided with suitable packing.

The valve has a stem, *J*, and to this is connected a lever, *F*, having suitable graduations upon it, and an adjustable weight, *G*. The lever is pivoted at the upper end of the branch *d*.

On the stem *J* is secured, just above the valve *e*, a diaphragm, *f*, the edges of which are clamped between the flanges *g h*. Above the diaphragm is secured the cap *i* by suitable bolts or screws.

The upper end of the branch *d* is provided with a curved pipe, *H*, to which a mercury-gage, *I*, is secured with its open branch, while the curved closed end is secured to a plate having flanges for the protection of the gage, and the graduations and numbers to indicate the amount of pressure in the vessel.

The branch *b* is provided with a cock, *B*, and this branch connects to a pressure-pump

or other vessel containing compressed air; and when it is desired to rack off the liquid, whatever it may be, whether water, beer, ale, or other liquids, the cock *B* is opened and the cock *C* is closed.

As it is desired to retain the absorbed gases in the liquid, therefore the space formed during the process of racking off is always filled with compressed air or gas, sufficient for the retention of the absorbed gases in the liquid, and for the racking off of the same.

An important feature of my invention is the valve-chamber, with its diaphragm and valve, which form together a differential piston-valve. The diaphragm has a larger area than the valve, so as to prevent the sticking of the valve on its seat, while at the same time the operation of the valve is made very sensitive by the pressure from the vessel containing the liquid against the under side of the diaphragm.

The weighted lever *F* tends to close the valve against the pressure on the diaphragm, and will, with the aid of the outflowing gas through the valve-seat *E*, close the valve instantaneously when the equilibrium of pressure on the diaphragm is disturbed.

To the end of the cock *C* suitable pipes may be attached, by which the escaping gas may be carried to any desired place.

I am aware that pressure-regulators provided with diaphragms have been heretofore used for regulating the pressure of liquids in vessels; but these differ entirely in construction and operation from mine, and I do not therefore broadly claim such; but,

Having thus described my invention, what I claim, and desire to secure by Letters Patent, is—

1. A pressure-regulator consisting of the body *A*, provided with a valve-chamber, *A'*, having channels *D E* and a valve, *e*, connected to a weighted diaphragm, *f*, all constructed and arranged for operation substantially as shown and specified.

2. A pressure-regulator consisting of the body *A*, with a valve-chamber, *A'*, having channels *D E* and a valve, *e*, connected to a weighted diaphragm, *f*, and branches *b* and *c*, provided with the cocks *B* and *C*, all constructed and arranged as shown and described.

3. A pressure-regulator consisting of the body A, with a valve-chamber, A', having channels D E and valve e, connected to a weighted diaphragm, f, in combination with the indicating mercury-gage I, all constructed and arranged for operation, as shown and herein described.

In testimony that I claim the above I hereunto set my hand.

F. W. WIESEBROCK.
